UNITED STATES PATENT OFFICE.

JAY G. RIDER, OF ROCKFORD, ILLINOIS, ASSIGNOR OF ONE-HALF TO CHARLES HERBERT LEWIS, OF ROCKFORD, ILLINOIS.

CIGAR AND CIGARETTE HOLDER.

1,289,267.

Specification of Letters Patent. Patented Dec. 31, 1918.

Application filed May 4, 1916. Serial No. 232,597.

To all whom it may concern:

Be it known that I, JAY G. RIDER, a citizen of the United States, residing at Rockford, in the county of Winnebago and State 5 of Illinois, have invented certain new and useful Improvements in Cigar and Cigarette Holders, of which the following is a specification.

This invention pertains to holders for carrying cigars and cigarettes while the same are being smoked. These holders are extensively used, because they afford a more convenient, sanitary and satisfactory means for carrying a lighted cigar or cigarette while 15 smoking, than by simply carrying the cigar or cigarette directly by the fingers and smoking by direct contact with the lips. The holders are characterized by a body provided at one end with a mouth piece or bit 20 and at the opposite end with a socket for the reception of one end of a cigar or cigarette for holding the same, the socket and mouth piece being connected by the usual draft passage. The cigar or cigarette must be firmly 25 pressed into the socket in order to hold, and because of the interposition of the holder, the cigar or cigarette is invariably smoked down to, or at least very close to the socket before the smoker is aware of the fact. To extract from the socket the short lighted end or 30 stub which has been firmly pressed therein, very frequently inconveniences the smoker. Either the fingers are burned or soiled, or some other means must be inserted in the 35 socket, and sometimes the holders are broken by knocking them against some hard object in the endeavor to dislodge the particles that cling to the walls of the socket.

In the present invention, I have aimed to 40 overcome these objections by the provision of an improved holder embodying means for ejecting therefrom the short end or stub of a cigar or cigarette left in the socket. This is accomplished in a very simple and practical manner by providing means operable 45 from the exterior of the holder for pressing the stub out of the socket. Such means in no way interferes with the ordinary holder construction, and in fact, various advantages 50 follow from its use, as will be evident and appreciated from the following description when considered in connection with the accompanying drawings, in which—

Figure 1 is a top view of a cigar or cigarette holder embodying my improvements;

Fig. 2, a longitudinal section through the holder, illustrating the ejector in normal position; and

Fig. 3, a similar view showing the ejector 60 in extended position.

The holder proper may be of any conventional design and construction, and it should be understood that my invention is in no way limited to the shape, form or dimensions of the holder. These are generally made in a single part or of a sectional construction in which the mouth piece or bit is screwed onto the part having the socket. The example illustrated in the drawing is of sectional construction, comprising a body portion 70 designated generally by character 4, provided at one end with a suitable socket 5 and having threadingly connected to its opposite end, a mouth piece or bit 6. The usual draft passage 7 connects the socket 5 with 75 the mouth piece. The socket, so far as the invention is concerned, is practically the same as found in any cigar or cigarette holder and may be of suitable size to receive either a cigar or cigarette or both, as the 80 case may be.

My invention contemplates the provision of an ejector normally disposed at the bottom of the socket and movable toward the mouth thereof by the manual operation of 85 means at the exterior of the holder, whereby the stub or short end of the cigar or cigarette may be forcibly pressed out of, or expelled from the socket. The ejector, preferably in the form of a plunger of the same, or practically the same, cross-sectional dimensions as the socket, is adapted to slide 90 out and in from and to its normal position. The ejector or plunger shown in the drawing and designated by reference character 8 is 95 disposed in an inward extension 9 of the socket 5, and in the present instance is shaped on its face to conform to the shape of the socket, although this is not necessary.

Means is now provided which may be manually operated from the exterior of the holder for moving the ejector 8 toward the mouth of the socket and for returning the ejector to normal position. This consists in the present instance of a rod 11 fixedly secured in any suitable manner to the ejector and extending through a passage 12 in the holder 4 substantially parallel with the passage 7, to a medial point at the exterior of the holder. The outer end of the rod 11 100

105

110

terminates in a suitable finger grip preferably formed by an annular groove 13 in the end of the rod. The plunger 8 is projected by pressing forwardly on the end 5 of the rod 11, and retracted by engaging the finger nail in the groove 13 and drawing the rod rearwardly. By reason of this construction the plunger 8 and rod 11 may be withdrawn through the socket 5 for cleaning. It will be especially noted that the draft passage does not continue through the plunger 8. Instead, however, the opening 9 is sufficiently large to allow passage around the plunger, thus providing an indirect 15 draft. This construction prevents nicotine from being easily drawn into the passage 7, as will be obvious.

The operation of my improvements is simple. The plunger 8 remains at the bottom of the socket when a cigar or cigarette is being held, and when the same is smoked down to or close to the holder, the stub may be quickly and fully ejected from the holder by shoving the end 13 forwardly by hand to 25 the position shown in Fig. 3. Thus the user does not soil or injure his fingers, and the inconvenience often experienced in removing the stub from cigar holders as formerly made, is entirely avoided.

30 It is believed that the foregoing conveys a clear understanding of my improvements and the objects prefaced above, and it should be understood that while I have illustrated and described one practical embodiment 35 thereof, various changes might be made in the construction and arrangement without departing from the spirit and scope of the invention as expressed in the appended claims, in which—

40 I claim:

1. A cigar or cigarette holder provided at one end with a mouth piece and at its opposite end with an open socket adapted to receive and hold a cigar or cigarette, and 45 having a draft passage between the socket and mouth piece, the medial portion of the holder being of less cross-sectional dimen-

sion than the socket end of the holder and having a passage substantially parallel with the draft passage and reaching from the 50 socket to the exterior of the holder, an ejector normally disposed in the bottom of the socket, and a substantially straight one piece actuating member connected to the ejector and slidably extending through the second mentioned passage in the body to the exterior thereof at the rear of the socket, the exterior end of said member being operable to move the ejector toward the mouth 55 of the socket to eject a stub or confined end 60 of a cigar or cigarette from the holder and being further movable through the passage to permit of the entire removal of the ejector and its operating member through the opening of the cigar holding socket. 65

2. A cigar or cigarette holder comprising a body provided at one end with a mouth piece and at its opposite end with an open socket adapted to receive and hold a cigar or cigarette and having a draft passage between the socket and mouth piece, an ejector 70 normally disposed in the bottom of the socket, and a single piece actuating member connected to the ejector, the body having a passage extending uninterruptedly substantially parallel with the draft passage from the socket to the exterior of the body at the rear of the socket, said member being normally slidably lengthwise through the second mentioned passage and snugly fitting 75 therein so as to preclude the admission of air through the passage to the socket or draft passage, the exterior end of said member being operable to move the ejector toward the mouth of the socket to eject a 80 stub or confined end of a cigar or cigarette from the holder and being further movable in its normal operative condition through the passage to permit of the entire removal of the ejector and its operating member 85 through the opening of the cigar holding socket. 90

JAY G. RIDER.
